UNITED STATES PATENT OFFICE

2,473,489

FLEXIBLE BAG WITH METAL GUSSET

Max Kaplan, New York, N. Y.

Application January 6, 1949, Serial No. 69,457

4 Claims. (Cl. 150—30)

1

This invention relates to containers, especially ladies' handbags, and more particularly to small bags for evening wear.

One type of lady's handbag which has proved to be popular for evening wear, is an envelope bag made of flexible material, for example, a rich faille fabric, closed at the ends by metal walls which are useful in maintaining the shape of the bag, and which are also ornamental in that they may be polished and plated with a precious metal, thereby contrasting with the fabric and enhancing the beauty of the bag.

The general object of the present invention is to improve bags, particularly bags of the specified character having metal ends. A more particular object is to improve access to the bag when opened. For this purpose I have devised flat gussets which are expandable, even though made of metal and hardly distinguishable from ordinary metal ends when the bag is closed.

To accomplish the foregoing general objects, and other more specific objects which will hereinafter appear, my invention resides in the bag elements and their relation one to another as are hereinafter more particularly described in the specification. The specification is accompanied by a drawing in which:

Fig. 1 is a perspective view of my improved bag in open condition;

Fig. 2 is a similar view showing the bag in closed condition;

Fig. 3 is a transverse section taken approximately in the plane of the line 3 of Fig. 1;

Fig. 4 is a fragmentary section taken in the plane of the line 4 in Fig. 3;

Fig. 5 is a fragmentary section similar to Fig. 3, but showing a modified motion limiting means;

Fig. 6 is a fragmentary section similar to Fig. 4, but taken in the plane of the line 6 in Fig. 5 and showing the modification;

Fig. 7 is a fragmentary section generally similar to Figs. 3 and 5, but showing still another modified form of motion limiting means;

Fig. 8 is a fragmentary section similar to Figs. 4 and 6, but taken in the plane of line 8 of Fig. 7, and showing the latter modification; and

Fig. 9 is a horizontal section through one end of the bag, taken in the plane of the line 9—9 of Figs. 2 and 4.

Referring to the drawings, and more particularly to Figs. 1 and 2, the container there shown has metal ends 12 and 14 permanently connected by a plurality of walls 16, 18 and 20 (Figs. 1 and 3) and having another wall 22 which is openable between the ends 12 and 14. The metal ends 12 and 14 are

2

and 14 are expandable to facilitate access to the container when the wall 22 is opened, and for this purpose each of the ends consists of two relatively movable plates 24 and 26 which are slideable over one another in face-to-face relation. In the preferred form shown the movable plates are pivoted at a point 28 which is remote from the openable wall 22. The ends 12 and 14 preferably are also provided with motion limiting means to limit the relative movement of the plates. This may comprise a projection 30 on one of the plates received in a slot 32 in the other of said plates, said slot following a path described about the aforesaid pivot 28 as a center.

In the form shown the ends 12 and 14 are rectangular, and are connected by three walls 16, 18 and 20, the openable wall 22 constituting a fourth wall to close the rectangle. This wall 22 is conveniently provided with a flap 34, and the flap 34 and the front wall 16 may be detachably connected by suitable fastener means, here illustrated as male and female snap fastener elements 36 and 38. The walls 16, 18, 20 and 22, and the flap 34 are all made of flexible material, and preferably of one continuous piece of such flexible material. As is customary in this art, the inside may be lined with a suitable lining material, and the edges of both the external material and the lining material may be folded inwardly and stitched together to provide a satisfactorily finished and thickened edge where the edge is exposed.

The plate 24 is bent or folded to form a channel 40 along one edge, the said channel receiving and being clamped about a portion of the edge of the flexible material. The other plate 26 is similarly provided with a channel 42 along the opposite edge, said channel being clamped about another portion of the edge of the flexible material. This construction will be evident from inspection of Figs. 1 and 2, and also from examination of Fig. 9 which shows how the free edges 44 of the channels 40 and 42 may be curled inwardly and clamped tightly against the flexible material, the latter being supported by the inner channel walls 46 and 48. The use of outwardly bent channels as shown has the further advantage that the channel wall 48 of plate 26 acts as a stop for the free edge of plate 24. It conceals and shields that edge when the bag is closed, so that the metal end is practically indistinguishable from an ordinary metal end of the non-expandable type.

The top edge of plate 24 is preferably folded inwardly and downwardly, as shown at 50 in Figs. 1, 3 and 4, thereby providing a guide channel

for the top edge of plate 26. This has two advantages, one being to give the exposed top edge of the metal a rounded edge, and the other being to hold the two plates closely in face-to-face relation.

The back wall of the handbag may be provided with a shallow pocket, indicated at 52 in Fig. 1. This may be done by reversely folding the lining material for a suitable distance. The pocket (for simplicity omitted in Figs. 3, 5, and 7) receives a comb, indicated in broken lines at 54 in Fig. 2. The main body of the bag may be used to receive a compact 56 and a lipstick 58, also shown in broken lines in Fig. 2. A support band, not shown, may be included for the lipstick. This, of course, is merely one example of possible contents for the bag, and would be appropriate only in the case of a very small evening bag.

In the form of the invention shown in Figs. 1 through 4, the projection 30 of the motion limiting means consists of a small tab of metal bent outwardly from the edge 60 (Fig. 3) of plate 26. To conveniently form the tab 30 in this manner, the edge 60 may be stepped back somewhat from the main edge 62 of plate 26. The slot 32 is cut entirely through the plate 24.

A modification of the motion limiting means is shown in Figs. 5 and 6 in which the projection 38 is received in a blind or closed slot 64, the said slot being formed by pressing the sheet metal of the outer plate 66 outwardly, instead of punching the slot therethrough.

Still another modification of the motion limiting means is shown in Figs. 7 and 8 in which the projection, instead of being a tab of metal bent from the edge of plate 70, is a dot or teat drawn or pressed sidewardly, as is indicated at 72. As here illustrated, the projection 72 cooperates with a slot 74 punched through plate 76. Another difference from the arrangement shown in Figs. 3 and 4 is that the slot is provided on the inner plate, while the projection is struck inwardly from the outer plate. Thus the slot is concealed from view, and the outside of the bag is unmarred.

It will be understood that the variant parts of the motion limiting means may be used in other combinations. For example, an arrangement as shown in Figs. 7 and 8 may be used with a blind slot or channel, as shown in Figs. 5 and 6. Moreover, the location of the slot and the projection as between the outer plate and the inner plate may be varied as desired.

It is believed that the method of constructing and using my improved container, as well as the advantages thereof, will be apparent from the foregoing detailed description thereof. Assuming the invention to be applied to a lady's evening bag, the bag, though made largely of flexible material, is kept in shape by metal ends, and is enhanced in appearance by the contrast between the precious metal on the ends, and the flexible material. However, the bag does not suffer from the disadvantage of having only a very narrow opening at the top when opened, and instead the front and rear walls may be spread apart much as though flexible gussets were employed at the ends. The expandible metal gussets which I have devised nest together so closely and inconspicuously that the bag is virtually indistinguishable from an ordinary non-expandible bag, except when opened.

It will be understood that while I have shown and described my invention in several forms,

many changes may be made in the structures disclosed without departing from the spirit of the invention, as sought to be defined in the following claims.

5 I claim:

1. A lady's handbag having metal ends permanently connected by front, bottom and back walls made of soft flexible, non-metallic material, and a flexible openable closure at the top of the bag, said metal ends being expandible to facilitate access thru the top of the bag when opened, each of said ends consisting of two overlapping metal plates pivoted at a point near the bottom wall, one of said plates having a channel along its front edge which receives and is clamped about an edge of the flexible front wall, the other of said plates having a channel along its rear edge which receives and is clamped about an edge of the flexible rear wall, and motion limiting means to limit the pivotal relative movement of the plates.

2. A lady's handbag having metal ends permanently connected by front, bottom and back walls made of soft, flexible, non-metallic material, and a flexible openable closure at the top of the bag, said metal ends being expandible to facilitate access thru the top of the bag when opened, each of said ends consisting of two overlapping metal plates pivoted at a point near the bottom wall, the front edge of one of said plates being bent outwardly, forwardly, and inwardly to form a channel which receives and is clamped about an edge of the flexible front wall, the rear edge of the other of said plates being bent outwardly, rearwardly, and inwardly to form a channel which receives and is clamped about an edge of the flexible rear wall, the other or free edge of the outer plate being shielded by the channel of the inner plate when the bag is closed, and motion limiting means to limit the pivotal relative movement of the plates.

3. A lady's handbag having metal ends permanently connected by front, bottom and back walls made of soft, flexible, non-metallic material, and a flexible openable closure means at the top of the bag, said metal ends being expandible to facilitate access thru the top of the bag when opened, each of said ends consisting of two overlapping metal plates pivoted at a point near the bottom wall, one of said plates having a channel along its front edge which receives and is clamped about an edge of the flexible front wall, the other of said plates having a channel along its rear edge which receives and is clamped about an edge of the flexible rear wall, the top edge of one of said plates being bent around the top edge of the other of said plates to provide a guide channel to hold the plates in close, face-to-face relation, and motion limiting means to limit the pivotal relative movement of the plates, said motion limiting means including a projection on one of the plates received in a slot in the other of said plates, said slot following a path described about the aforesaid pivot as a center.

4. A lady's handbag having metal ends permanently connected by front, bottom and back walls made of soft, flexible, non-metallic material, said handbag having a top wall openable between said ends, and a flap forming an extension of said top wall at the front of the bag, all of said walls and flap being made of a single continuous piece of soft, flexible, non-metallic material, said metal ends being expandible to facilitate access thru the top of the bag when opened, each of said ends consisting of two overlapping metal plates

pivoted at a point near the bottom wall, one of said plates having a channel along its front edge which receives and is clamped about an edge of the flexible front wall, the other of said plates having a channel along its rear edge which receives and is clamped about an edge of the flexible rear wall, and motion limiting means to limit the pivotal relative movement of the plates to an amount at their upper ends nearly equal to their width, thereby nearly doubling the opening at 10 the top of the bag.
